UNITED STATES PATENT OFFICE.

ERNEST J. ALLEN, OF ALBANY, NEW YORK, ASSIGNOR TO RATHBONE, SARD & COMPANY, OF ALBANY, NEW YORK, A CORPORATION.

GAS-STOVE.

1,160,486.

Specification of Letters Patent. Patented Nov. 16, 1915.

Application filed March 26, 1914. Serial No. 827,471.

To all whom it may concern:

Be it known that I, ERNEST J. ALLEN, a subject of King George V of Great Britain, residing at the city of Albany, in the county 5 of Albany and State of New York, have invented certain new and useful Improvements in Gas-Stoves, of which the following is a specification.

My invention relates to gas stoves, and 10 the object of my invention is to provide a means for supplying gas to a burner, properly mixed with air and in such quantities as is desired, with means for providing the same proportionate amount of air and gas 15 regardless of the quantity of the mixed fluid delivered for burning; together with such elements and combinations as are hereinafter more particularly set forth and claimed. I accomplish these objects by means of the 20 mechanism illustrated in the accompanying drawings, in which:

Figure 1 is a section of the mixing valve. Fig. 2 is a section along the lines, A—A, on Fig. 1. Fig. 3 is a section along the lines, 25 B—B, on Fig. 1. Fig. 4 is an elevation of the valve plug. Fig. 5 is a side view of the valve plug. Fig. 6 is an end view of the sliding block. Fig. 7 is a plan of the sliding block. Fig. 8 is a plan of the adjusting 30 screw. Fig. 9 is a plan of the manifold. Fig. 10 is a section along the lines, A—A, on Fig. 9. Fig. 11 is an elevation of the apparatus assembled and ready for use. Fig. 12 is a vertical section through the dia- 35 phragm, 16. Fig. 13 is a cross section through the diaphragm, 16.

Similar letters refer to similar parts throughout the several views.

The manifold comprises a casting, A, pro- 40 vided with two disconnected chambers, B and C. The chamber, C, contains air and the chamber, B, gas. The air enters the chamber, C, through the pipe, D, and the gas pipe, E, conducts gas to the chamber, 45 B. From the chamber, B, the gas escapes through the orifice, F, into the opening, G, in the mixing valve, V, and through the opening, H, air from the chamber, C, enters the opening, J, in the mixing valve. Con- 50 trolling the openings, G, and J, is a valve stem, K, carrying a plug, L, thereon into which is cut a slotted opening, M, which during the rotation of the valve stem, K, may be brought to register with the gas in- 55 let, G, permitting gas to flow through the

opening in the plug into the mixing chamber, N, in such quantity as is desired, be- 60 cause the slotted opening may be brought by the rotation of the plug so that a very small orifice is presented for the passage of gas; or a larger orifice is so presented, depending upon the desire of the operator. The valve stem, K, also carries the bifurcated plug, O, through which is the passage- 65 way, U, so arranged in reference to the air inlet, J, that the amount of air which may be allowed to enter the mixing chamber, N, may be regulated by the rotation of the stem and plug.

The size of the space, P, through the bi- 70 furcated plug, O, is such in proportion to the size of the slotted opening, M, in the plug, L, that the proportion of the quantity of gas and air admitted into the mixing chamber, N, will be the same whether the 75 quantity of each is very large or very mi- nute. But there is always some air admitted through the opening, U, to the mixing chamber, N, as is shown in Fig. 1, which 80 illustrates the position of the valve when the gas is entirely cut off, for a portion of the opening, U, registers with the chamber, B, and a small quantity of air flows into the burner, 14, which prevents "back-fir- 85 ing". The function of the opening, U, is to provide for a small quantity of air being carried into the mixing chamber just 90 previous to the stopping of the flow of gas and thus maintaining a constant flow through the burner, purging the burner of explosive 95 gas. This "back-firing" is occasioned by the flame igniting the little gas in the burner, which has not sufficient pressure to be driven out of the burner quickly and which therefore explodes in the burner. By 100 supplying air after the gas has been turned off, the gas is driven out of the burner to the flame and prevents the interior explosion.

For the purpose of adjusting the valve 105 stem, K, so that the plugs, L and O, thereon may be adapted for a very rich gas, or gas that is not so rich I place a sliding block, S, adapted to reciprocate between the bifurcations in the space, P, of the plug, O, and adjusted by means of the screw, T, so that the opening through the bifurcated plug, O, may be partly closed but not suffi- 110 ciently to close the passageway, U when desired.

From the mixing chamber, N, the gas es-

capes through a suitable opening, W, to burner, 14, shown in Fig. 11. A handle, Y, attached to the stem, K, is a convenient means for rotating the stem. The finger, X, on the handle may be arranged to register with the table, Z, upon which suitable figures or letters (not shown) may be placed for the purpose of indicating what the degree of the gas and air openings may be, which 10 openings have been caused by the rotation of the valve stem, and which is shown by the position of the finger.

For the purpose of maintaining substantially the same proportion of air to gas when 15 the pressure of gas varies, I have provided an automatic means for opening and closing the valve in the air supply pipe, D. I have provided a branch, 15, leading from the gas supply pipe, E, to a diaphragm casing, 16. Within the casing, 16, is an ordinary diaphragm, 25, one side of which is acted upon by the gas delivered through the branch, 15. For the purpose of carrying the air from the air chamber, C, to the diaphragm, maintaining a pressure on the diaphragm equal to that of the pressure in the chamber, C, the pipe, 19, communicates with the air chamber, C, in the manifold so that the air flowing through the pipe, 19, impinges upon the side of the diaphragm opposite that upon which the gas impinges. The butterfly valve, 17, is connected to the diaphragm 25, by means of the link, 26, crank, 27, and rocking arm, 28, and so arranged that the pressure of the gas on the diaphragm will open the valve, 17, the degree of the opening depending upon the degree of pressure of the gas. The valve, 17, is so adjusted that the proper amount of air to gas 40 will be furnished because of the effect of the gas upon the butterfly valve. Thus with a gas of greater pressure the valve is opened wider than when a gas of lower pressure is furnished, and therefore more air is admitted 45 to the air chamber thence to the mixing chamber. Gas pressure from the main opens valve, 17, until air pressure from the manifold equals the gas pressure. The pressures are thus balanced.

50. What I claim as my invention and desire to secure by Letters Patent is:

1. In a gas burner, a valve comprising a casting provided with a mixing chamber; a valve stem; a plug thereon provided with a 55 restricted opening in a plane at right angles to the axis of the valve stem; an opening in the casting with which said restricted opening in the plug may register when the stem is rotated; a bifurcated plug on said 60 valve stem; a passageway through the legs of said plug in a plane at right angles to

the axis of the plug, said passageway adapted to register with an opening in the valve casing during the rotation of the stem; a sliding block adapted to reciprocate between 65 the legs of said plug; and means for regulating the position of said block between the legs on the plug.

2. In a gas burner, a mixing valve; means for conveying gas and means for conveying 70 air thereto; means for automatically apportioning the volume of air to that of gas in its admission to the mixing chamber; with a means for causing air to pass into the burner after the gas has been cut off.

75. 3. The combination of a manifold, comprising two non-communicating chambers; means for conveying gas to one of said chambers; means for conveying air to the other chamber, with a gas burner, and connected therewith a mixing valve provided with a mixing chamber and a valve stem; and means carried by said valve stem for maintaining the admission of air and gas from the manifold to the mixing chamber in 80 the same proportion of gas to air, regardless of the quantity of either, so that by the movement of the valve stem to cause an increased flow of gas, a proper amount of air will be supplied without any adjustment or 85 further manipulation of the apparatus by the user.

4. In a gas burner, a mixing valve, comprising a mixing chamber; a valve stem; means connected with and operated simultaneously with said valve stem for providing for the gas and air to enter the mixing chamber in certain predetermined proportions; with means also connected with and operated by said valve stem for causing the 95 delivery of a small quantity of air into the mixing chamber just previous to the stopping of the flow of gas, thus maintaining a flow through the burner, purging the burner of explosive gas and preventing back-fire; 100 with means for rotating said valve stem; and means for indicating the degree of rotation thereof.

105. 5. In a gas burner, a valve provided with a mixing chamber and a valve stem, said valve stem provided with a restricted opening in a plane at right angles to the axis of the valve stem; a bifurcated plug on said valve stem; and a passageway through the legs of said plug in a plane at right angles 110 to the axis of the plug.

In testimony whereof I have affixed my signature in presence of two witnesses.

ERNEST J. ALLEN.
